UNITED STATES PATENT OFFICE.

JAMES E. SIMPSON, OF BROOKLYN, NEW YORK, ASSIGNOR TO CORONA TYPEWRITER COMPANY, INC., OF GROTON, NEW YORK, A CORPORATION OF NEW YORK.

LINE-RULING DEVICE FOR TYPE-WRITING MACHINES.

1,311,921.

Specification of Letters Patent.

Patented Aug. 5, 1919.

Application filed July 17, 1917, Serial No. 180,974. Renewed December 31, 1918. Serial No 269,176.

To all whom it may concern:

Be it known that I, JAMES E. SIMPSON, a citizen of the United States, and resident of the borough of Brooklyn, county of Kings, 5 city and State of New York, have invented certain new and useful Improvements in Line-Ruling Devices for Type-Writing Machines, of which the following is a specification.

10 This invention relates to line-forming devices for typewriting machines, and it has particular reference to means, attachable to machines of various makes or forming a permanent part of the equipment thereof, 15 whereby in the movement of the paper carriage longitudinal lines may be drawn, and in the revolving movement of the platen vertical lines may be drawn.

One of the objects of the invention is to 20 provide a line ruling device which is normally out of contact with the paper platen but which may be moved to cause the line ruling wheel to engage the platen, yieldable means being provided to hold the line ruling 25 wheel in the desired relation to the platen.

Another object of the invention is to provide a line ruling device with a line marking wheel and a rotatable inking roll, and to cause the inking roll or pad to move transversely of the line marking wheel whereby substantially the entire surface of the inking pad will be caused to engage the marking wheel. The purpose of this is to prevent 30 the marking wheel wearing a groove in the 35 inking roll.

Another object of the invention is to provide means operated through the rotation of the marking wheel to shift the inking roll laterally to thereby cause substantially its 40 entire inking surface to contact with the marking wheel.

Another object of the invention is to provide a rotatable holder carrying the marking wheel and the inking roll, and to provide a 45 stop to limit the rotary movement of the said holder and to enable the operator to accurately position the marking wheel for ruling either horizontal or vertical lines.

There are other important objects and 50 advantages of the invention all of which will appear more fully hereinafter.

In the drawing, Figure 1 is a vertical longitudinal sectional view taken on the line 1—1 of Fig. 2;

55 Fig. 2 a plan view of the device applied to a typewriter frame;

Fig. 3 a transverse vertical sectional view on the line 3—3 of Fig. 2;

Fig. 4 a longitudinal vertical sectional view on the line 4—4 of Fig. 2; and 60

Fig. 5 a detail side elevation of the marking wheel.

Referring to the various parts by numerals, 1 designates a permanent part of a typewriter frame, and 2 the platen. Secured 65 to the typewriter frame is an upwardly extending bracket 3, in the upper end of which is formed a horizontal journal part 4. Mounted in this journal is a horizontal rod 5, carrying at its forward end a finger piece 70 6 by means of which the bar 5 may be rotated and pressed rearwardly, as herein-after described. The bar 5 is formed with a squared rear portion 7, on the rear end of which is secured a rearwardly extending 75 frame 8. Between the finger piece 6 and the journal bearing 4, and surrounding the rod 5, is a spring 9 which normally retracts the bar 5 and holds the stops 10 and 11 against the journal bearing. Secured to the bracket 80 3 and bearing against one side of the squared portion 7 of the rod 5 is a flat spring 12, said spring serving to hold the rod and the connected frame 8 in either the position shown in Fig. 1 or in a partly rotated position in 85 which the line ruling wheel will be in a horizontal position, as will be hereinafter described.

In the rear end of the frame 8 is mounted a shaft 13 to which is secured the line ruling 90 or marking wheel 14, said wheel being formed with a narrow periphery for marking purposes and which is adapted to be brought into engagement with the paper sheet on the platen 2. Carried by the marking wheel, on one side thereof, is a cam 15, said cam extending only partly around the marking wheel as indicated clearly in Figs. 2 and 5. Loosely mounted in the frame 8 is a transverse journal rod 16, said rod extending loosely through apertures 17 in the sides of the frame 8. Loosely mounted on this journal rod is an inking roll 18 which is adapted to bear against the periphery of the marking wheel 14, the said inking 100 roll being somewhat larger in diameter than the marking wheel as shown clearly in Figs. 1 and 2 of the drawings. Rigidly secured to the forward cross bar 19 of the frame 8 are two springs 20 whose rear ends engage 105 in grooves in the journal bar close to the

inner surfaces of the side bars of the frame 8, as shown clearly in Fig. 2, said springs 20 forcing the journal bar rearwardly and causing the inking roll to yieldingly engage 5 the periphery of the marking wheel. The springs 20 also serve as latch devices for holding the journal bar in position in the frame 8. The inking roll may be removed from the frame by forcing the journal bar 10 axially through the frame, the springs 20 yielding to a suitable endwise pressure on said bar. Loosely pinned to the forward cross bar of the frame 8 is a rearwardly extending yoke 21, the arms 22 of which extend 15 on either side of the inking roll and are apertured for the passage of the journal rod. The rear end of one of said arms 22 is adapted to be engaged by the cam 15 on the marking wheel and to follow said cam 20 during the rotation of said wheel. A spring 23 is carried by the frame 8 and bears against the outer side of the arm 22 which engages the cam 15, and yieldingly holds said arm in engagement with said cam. 25 The yoke 21 is loosely pinned to the frame 8 in order that it may be moved laterally by means of the cam 15. The arms 22 of said yoke are close to the sides of the inking roll so that as the yoke is vibrated laterally 30 it correspondingly moves the inking roll on the journal rod.

The bracket 3 is formed with a rearwardly extending stop lug 24 which is adapted to be engaged by the lugs 10 and 35 11. When the stop lug 11 is in engagement with the stop lug 24 the marking wheel is in position to rule vertical lines on the paper carried by the platen 2. By rotating the bar 5 in the direction indicated by the 40 arrow B in Fig. 3, the lug 10 will be brought into engagement with the stop lug 24 to hold the marking wheel in a position to roll horizontal lines on the paper carried by the platen. To bring the stop lug 11 into 45 engagement with the stop 24 the rod 5 is rotated in the direction indicated by the arrow marked A in Fig. 3. The spring 12 serves to yieldingly hold the rod 5 in its adjusted position, the coöperating stops 10, 50 11 and 24 serving to accurately position the marking wheel for marking either horizontal or vertical lines, as desired. The stop lug 24 is of sufficient length to permit the lugs 10 and 11 to remain in engagement 55 therewith when the frame 8 is projected rearwardly to bring the marking wheel into engagement with the paper carried by the platen.

It is manifest that by reason of the variation 60 in the diameters of the marking wheel and the inking roll the periphery of the marking wheel will eventually be brought into engagement with substantially the entire inking surface of the inking roll. It is 65 also manifest that the marking wheel will

not run in the same path on the inking roll throughout the rotation of said roll, but that the said path will vary in successive rotations of the inking roll and that all danger of wearing a groove or fixed path 70 or orbit in the inking roll will be avoided.

It will, of course, be understood that any suitable means may be employed for supporting the inking roll to permit it to have a lateral movement through the operation 75 of the marking wheel. It is also manifest that the details of construction may be considerably varied within the scope of the invention; for instance any suitable means may be provided for stopping the rod 5 at 80 the proper points in its rotation to accurately position the marking wheel for ruling either horizontal or vertical lines.

What I claim is:

1. A line-forming device comprising a 85 line marking wheel, an inking roll engaging said marking wheel, and means operated by the marking wheel for laterally shifting the inking roll during the rotation of the marking wheel.

2. A line-forming device comprising a line marking wheel, an inking roll engaging said marking wheel, and means for laterally shifting the inking roll during the rotation 90 of the marking wheel.

3. A line-forming device comprising a frame, a line-forming wheel journaled in said frame, an inking-roll shaft removable endwisely from said frame having its ends rotatably and shiftably supported in elongated apertures formed in opposite sides of the frame, an inking roll loosely mounted on said shaft, and yieldable means for releasably holding said shaft against endwise movement in the frame and for forcing said shaft laterally toward the line-forming 100 wheel.

4. A line-forming device comprising a line marking wheel, an inking roll, a cam carried by the marking wheel, and means 110 adapted to be engaged by said cam during the rotation of the marking wheel to shift the inking roll laterally.

5. A line-forming device comprising a shiftable frame, a marking wheel journaled 115 in said frame, an inking-roller shaft supported in the frame, an inking roller of greater diameter than said marking wheel loosely journaled on said shaft and engaging the marking wheel, and means for automatically shifting said inking roller back and forth along its shaft during rotation of the marking wheel.

6. The combination with a typewriting machine, of a line-forming device comprising a frame rotatably supported on a part of the machine frame and reciprocable toward and from the platen, a marking wheel mounted in said rotatable and reciprocable frame, a cam rotatable by said marking 125 130

- wheel, an inking roll mounted in said rotatable and reciprocable frame, means operated by said cam to shift the inking roll laterally relatively to the marking wheel in one direction, and means tending to normally force the inking roll laterally in the opposite direction.
7. A line-forming device comprising a frame, a line marking wheel mounted thereon, a cam formed on said wheel, an inking roll journaled in said frame, an arm shiftably supported in said frame and adapted to be engaged by the said cam, means for yieldingly pressing said arm against the cam, and means whereby the vibration of said arm will laterally shift the inking roll.
8. A line-forming device comprising a reciprocable frame, a line marking wheel mounted therein, a cam formed on said wheel, a journal rod mounted in said frame, means for yieldingly holding said rod in said frame and pressed toward the marking wheel, an inking roll loosely mounted on said journal rod, a yoke embracing said inking roll and loosely mounted in the frame, one arm of said yoke engaging the cam on the marking wheel, and means yieldingly holding one arm of said yoke against said cam.
9. A line-forming device comprising a stationary support, a rod rotatably mounted in said support and reciprocable relatively thereto, a marking wheel carried by said rod, an elongated fixed stop on said support, a pair of spaced stops on said rod adapted to engage said elongated stop to limit the extent of rotation of the rod in either direction to position the marking wheel for forming lines at different angles, and yieldable means frictionally engaging said rod to hold either of the stops carried thereby in engagement with said elongated stop during reciprocation of the rod relatively to its support.
10. A line-forming device comprising a stationary support, a marking wheel, a support for said marking wheel rotatably and reciprocably mounted on said stationary support, and coöperating abutments carried by said supports adapted to limit the extent of rotation of the wheel support and to guide the wheel in its rotatably adjusted position toward and from marking position when the wheel support is reciprocated relatively to the stationary support.
11. A line-forming device comprising a stationary support, a marking wheel, a support for said marking wheel rotatably and reciprocably mounted on said stationary support, coöperating abutments carried by said supports adapted to limit the extent of rotation of the wheel support and to guide the wheel in its rotatably adjusted position toward and from marking position when the wheel support is reciprocated relatively to the stationary support, and yieldable means held to said stationary support and frictionally engaging said wheel-support to maintain the coöperating abutments in engagement with each other during reciprocation of the wheel support.
12. A line-forming device comprising a stationary support, a marking wheel support rotatably and reciprocably mounted on said stationary support, a marking wheel journaled in said wheel support, an inking-roll shaft journaled in said wheel support, an inking roll loosely mounted on said shaft and engaging the marking wheel, a yoke embracing the inking roll, and means controlled by the rotation of the marking wheel for imparting a reciprocatory movement to said yoke to shift the inking roll longitudinally of its shaft.
13. A line-forming device comprising a holding frame, a line forming wheel mounted therein, an inking roll, a longitudinally movable journal rod for said inking roll, and yieldable means for holding said rod in the frame.

This specification signed this fourteenth day of July, A. D. 1917.

JAMES E. SIMPSON.
